UNITED STATES PATENT OFFICE.

JOHN ZILLIOX, OF ORCHARD PARK, NEW YORK.

BOILER-TUBE CLEANER.

1,363,301.

Specification of Letters Patent. Patented Dec. 28, 1920.

Application filed November 14, 1919. Serial No. 338,025.

To all whom it may concern:

Be it known that I, JOHN ZILLIOX, a citizen of the United States, residing at Orchard Park, in the county of Erie and State 5 of New York, have invented new and useful Improvements in Boiler-Tube Cleaners, of which the following is a specification.

This invention relates to a boiler tube cleaner of that type in which a hammer 10 operated by a pressure fluid is employed for removing the incrustation or scale from the boiler tubes or flues by rapid blows.

It is the object of this invention to provide a boiler tube cleaner of this character 15 which contains a considerably fewer number of parts than those heretofore in use for this purpose, and to so organize these parts that the same can be produced at very much lower cost and will operate efficiently and 20 economically without undue wear or liability of getting out of order.

In the accompanying drawings: Figure 1 is a longitudinal section of my improved boiler tube cleaner taken on a plane parallel with the direction of movement of the hammer. Fig. 2 is a similar view, taken on a plane at right angles to the direction of movement of the hammer. Figs. 3, 4 and 5 are transverse sections taken on the correspondingly-numbered lines in Fig. 1. Fig. 30 6 is a fragmentary elevation of the slide valve which controls the admission to and the exhaust of the pressure medium from the opposite ends of the power cylinder 35 which forms part of the mechanism for actuating the hammer.

Similar characters of reference indicate corresponding parts throughout the several views.

40 The body of this tube cleaner consists essentially of an outer tubular shell or casting 10 and a core or plug 11 arranged within the shell. At its rear end the shell is provided with an inlet or chamber 12 for steam or similar pressure medium, whereby the movable parts of the tube cleaner are 45 operated and which is supplied to this inlet or chamber by means of a tube 13 or any other suitable means. On the central part 50 of the shell the same is provided with an internal forwardly-projecting shoulder 14 and at its front end the same is provided with an internal screw thread 15.

The front part of the core is of the same

external diameter as the bore of the front 55 part of the shell and fits tightly therein, so as to form practically a steam tight joint therewith. At the rear end of the enlarged part of the core the same is provided with a rearwardly-facing annular shoulder 16 60 which bears against the internal shoulder 14 of the shell, so as to limit the backward movement of the core in the shell, and these parts are firmly held in this position by means of a clamping device mounted on the 65 front end of the shell and engaging with the front end of the core. This clamping or retaining device in its preferred form consists of a ring 17 having an external screw thread which engages with the internal 70 thread 15 of the shell and bears with its rear side against the front end of the core. In order to prevent this retaining or clamping ring from becoming loose under the vibrations to which the same is subjected 75 while the tube cleaner is in use, a locking device is provided which preferably consists of a locking pin 18 having an external screw threaded rear end which engages with an opening 19 in the front end of the core 80 while its front part is adapted to engage with one or another of a plurality of notches 20 arranged in an annular row in the inner edge of the retaining ring 17, as shown in Figs. 1, 2 and 3. A sufficient number of 85 these notches is provided in the retaining ring, so that when the same has been tightened as firmly against the core as is necessary to hold the latter in place, one or the other of these notches will be either in line 90 with the pin opening 19 in the core or adjacent thereto, so that but a slight loosening of the ring is necessary in order to permit of engaging the locking pin 18 with the opening 19 and the adjacent notch 20 of the 95 ring, so that thereafter this ring is positively held against unscrewing. In order to prevent the locking pin 18 from unscrewing under the vibrations to which the same is subjected, a cotter pin or key 21 is passed 100 through the outer end of the locking pin 18, which key or cotter pin is adapted to engage with the adjacent inner side or bore of the retaining ring 17 and thus prevent the locking pin 18 from unscrewing.

105 The rear part 22 of the core is reduced as compared with the front part thereof, so as to form an annular space between the same

and the adjacent inner wall or bore of the shell which constitutes the inlet or pressure chamber 12 of the apparatus. This reduced part of the core is preferably provided with two flat parallel outer sides or faces 23 one of which, as shown in Figs. 2 and 5, is engaged by a lug 24 formed on the inner side of the shell and operates to hold the core against turning in the shell and thus 10 avoids displacement of the parts relatively to each other.

Within this reduced rear part of the core is formed a transverse cylindrical slide valve guide-seat 25 which opens at its opposite 15 ends into the inlet chamber 12, so as to admit the pressure medium thereto. Adjacent to the front end of the enlarged part of the core the latter is provided with a transverse power cylinder 26 which forms part 20 of the motor whereby the movable parts of the tube cleaner are actuated. The opposite ends of this power cylinder are closed by the adjacent parts of the shell or casing 10 which form heads for this cylinder. 25 Each end of the power cylinder is connected on one side with the corresponding end of the cylindrical valve seat 25 on the front side of the latter by means which conduct the pressure medium from the valve seat to 30 the respective end of the power cylinder and back again, these conducting means being preferably constructed in the form of a multiple port or passage, which in its preferred form consists of three sections 27 arranged lengthwise side by side in the core and extending from the front side of the circular valve seat to the rear side of the power cylinder, as shown in Figs. 1, 4 and 5. The front part of each of these conduit 35 sections incline inwardly from the respective end of the power cylinder toward the axis of the tube cleaner while the rear part thereof is parallel with this axis, thereby bringing the rear ends of the supply passages on opposite sides of the axis of the cleaner closer together so as to require a shorter valve for controlling the same, while the front ends of the two sets of these 40 passages are spread apart in order to reach the extremities of the power cylinder. Each of these several conduit sections is preferably bored by means of a tool which enters the core through one of the outer ends of the power cylinder which operates to produce the inclined front part of the respective supply passage, while the parallel rear part thereof is produced by a similar operation of a boring tool which approaches the core from the rear end of the enlarged part of 45 the core. By thus forming each of the supply passages in the form of a plurality of bored sections instead of forming each of these passages in one section, it is possible to produce the core of hard material such as 50 steel by machining the same instead of pro-

ducing this particular member in the form of a casting which is inferior for this particular work.

Extending lengthwise through the front or enlarged part of the core from the central part of the front side of the sliding valve seat to the front end of the core is an outlet or exhaust passage which consists of two curved central parts 28 extending around the central part of the power cylinder, a longitudinal rear part 29 extending from the curved parts 28 to the central part of the valve seat between the supply passages 27, and a longitudinal front part 30 extending from the front ends of the curved 75 parts 28 to the front end of the core.

31 represents a power piston which is arranged in the power cylinder 26 and which is reciprocated therein by alternately admitting the pressure medium into and exhausting the same from the opposite ends of this cylinder. This piston is preferably provided in its opposite ends with cavities 32 for the purpose of making the same as light as possible and thereby reducing to a 85 minimum the inertia of the piston as the same is reciprocated, so as to avoid undue wear on the parts as well as eliminating unnecessary noise due to the constant reversal 90 in the movement of this piston in this cylinder. The pressure medium is alternately admitted from the inlet chamber 12 to opposite ends of the power cylinder and also alternately exhausted from the opposite ends 95 of the latter through the exhaust passage 100 in the core by means of a valve 33 which is of cylindrical form and reciprocates transversely in the guideway 35. This slide valve is provided on its front side with a cavity 34 which faces that side of the bore of the 105 seat 25 into which the rear ends of the supply passages 27 and the exhaust passage of the core open. The length of the slide valve 33 and its cavity 34 are so determined that when this valve is in its uppermost position, as indicated in Figs. 1 and 5, the lower 110 end of this valve will uncover the lower ports or passages 27 and permit the pressure medium to pass from the inlet or supply chamber 12 into the lower end of the cylinder 26 for raising the piston, while the cavity 34 of the valve connects the rear end 115 of the upper set of ports 27 with the rear end of the exhaust passage and thereby permits the spent pressure medium to escape 120 from the upper end of the power cylinder to the atmosphere at the front end of the apparatus. When the slide valve 33 is in its lower or reverse position from that shown 125 in Figs. 1 and 5, the upper set of ports 27 will be placed in communication with the pressure supply chamber 12 and permit the pressure medium to enter the upper end of the power cylinder for driving the piston therein downwardly while the cavity 34 of 130

the slide valve places the lower set of ports 27 in communication with the exhaust passage and thereby permits the spent pressure medium to escape from the lower end of the 5 power cylinder to the atmosphere.

In order to hold the slide valve firmly 10 against that side of its seat which contains the ports 27 and the exhaust passage, an 15 opening 35 is formed in the contracted rear part of the core leading from the rear side of the valve seat to the pressure supply 20 chamber 12, so that the pressure medium is permitted to bear against the rear side of the valve 33 and force the same forwardly 25 against the front side of this seat, thereby 30 maintaining a tight joint between the front side of this valve and the corresponding side of the valve seat, so that leakage between 35 these two members is positively prevented 40 and the maximum efficiency from the pressure medium for operating the tube cleaner is obtained.

Means are provided for alternately shifting 45 the slide valve 33 in opposite directions by motion which is derived from the power 50 piston, which means are so constructed that they also serve to produce the blows against the tubes whereby the scale or incrustation thereon is removed. As shown in Figs. 1-5, 55 these means comprise a longitudinal hammer lever extending lengthwise through the exhaust passage and through a longitudinal opening 36 formed diametrically in the power piston and having a rear arm 37 which is operatively connected with the 60 valve, and a front arm 38 which extends forwardly beyond the body of the tube cleaner and is provided at its front end with a hammer head 39 which is adapted to strike 65 the boiler tubes or flues for cleaning the same. Between its front and rear arms this hammer lever is pivotally mounted upon the core between the power piston and the slide valve by means of a pin 40 which extends 70 through an opening in the hammer lever and is journaled at its opposite ends in bearing 75 openings 41 formed in the adjacent part of the core, thereby forming a pivotal connection 80 between the hammer lever and the core which permits the hammer lever to 85 swing crosswise of the body. At its rear end the rear arm of the hammer lever is provided with a spherical enlargement or 90 knuckle 42 which engages with a cylindrical 95 recess 43 formed in the central part of the valve 33 and extending rearwardly from the bottom of the cavity 34 therein, thereby 100 forming a pivotal connection between this valve and the hammer lever whereby motion 105 is imparted to the valve and still permits the valve to move in a rectilinear path while the knuckle 42 moves in a circular path.

Within the diametrical opening 36 of the piston the hammer lever is provided with a 110 spherical enlargement or knuckle 44 which

fits this cylindrical opening and forms a sliding connection between the hammer lever and the piston, so that motion is transmitted from the piston to the hammer lever but the latter is permitted to work in the piston the 70 requisite extent to avoid any binding action. It will be obvious from this construction that when the front arm of the hammer lever is moved upwardly from the piston indicated in Fig. 1 by the admission of the pressure fluid underneath the piston 31, that the rear arm of this lever will at the same time move the valve 33 downwardly, while upon moving the piston 31 downwardly the valve 75 will be moved upwardly, thereby continually 80 reversing the connections between the pressure supply and opposite ends of the power cylinder, and between the latter and the exhaust while the apparatus is in operation.

The hammer lever, together with the hammer head and the knuckles 42 and 44 formed on the rear and front arms thereof, are all formed out of a single piece of metal in any suitable manner, thereby not only simplifying the construction but also reducing the 90 number of parts which enter into the composition of the cleaner and also avoiding loosening of any parts which otherwise would be liable to occur if the same were made separate and connected with each 95 other. The making of the hammer lever together with its coupling knuckles and hammer head in one piece and the proper assemblage of the same with the core, piston and valve is rendered possible by making the 100 several parts of the hammer progressively smaller from its front end toward its rear end, that is to say, the hub 45 of the lever which receives the pin 40 is of smaller 105 diameter than the front knuckle 44 which engages with the piston, and the rear knuckle 42 is of smaller diameter than the hub 45, thereby permitting the lever to be passed through the core, the piston and into the slide valve 33 from the front end of the 110 core toward the rear end thereof, and also permitting the hammer head 39 to be formed integrally with the hammer lever.

As a whole the organization of this boiler tube cleaner comprises few parts, the same 115 coöperate in a manner which permits of producing a powerful blow of the hammer which operates to efficiently clean the tubes, and the several parts are so disposed as to produce a minimum wear on the same as 120 well as utilize the pressure medium most efficiently and economically.

I claim as my invention:

1. A boiler tube cleaner comprising a body having an inlet at its rear end for a 125 pressure medium, a transverse slide valve seat in its rear part, a transverse motor cylinder in its front part, supply passages connecting opposite ends of the valve seat with opposite ends of the cylinder, and an ex- 130

haust passage extending from the central part of said valve seat to the front end of the body, a transverse pivot pin arranged on the body between said cylinder and valve seat, a piston arranged in said cylinder and provided with a diametrical opening, a slide valve movable on said seat and having a cavity on its rear side and adapted to connect said inlet and exhaust passage alternately 5 with said supply passages and provided in the bottom of said cavity with a recess, and a hammer having a lever which is arranged in said exhaust passage and mounted on said pin and provided with a rear arm having a spherical rear end which engages with said recess, and a front arm provided intermediate of its ends with a spherical enlargement which engages with said opening in the piston and provided at its front end with a 10 hammer head, said lever and its head and spherical enlargements being constructed of a single piece, the spherical enlargement on the rear arm of the hammer lever being smaller than the spherical enlargement on 15 the front arm of the same.

2. A boiler tube cleaner comprising a body having an outer tubular shell and an inner core, said shell being provided at its rear end with an inlet for a pressure medium, said core being provided at its front end with a transverse power cylinder, at its rear end with a reduced portion containing a transverse cylindrical valve seat, longitudinal supply passages connecting the corresponding outer ends of the valve seat and power cylinder and an exhaust passage extending forwardly from the central part of the valve seat, a lug arranged on the inner side of said shell and engaging said reduced 20 rear part of the core, a piston arranged in said cylinder, a cylindrical slide valve engaging said seat, and a hammer having a lever pivoted on said core and provided with a rear arm which engages said valve and a front arm which engages said piston, and a hammer head arranged on the front arm of the hammer lever.

3. A boiler tube cleaner comprising a body having an outer tubular shell and an inner core, said shell being provided at its rear end with an inlet for a pressure medium, said core being provided at its front end with a transverse power cylinder, at its rear end with a reduced portion containing a transverse cylindrical valve seat and an opening extending from the rear side of the central part of said valve to said inlet, longitudinal supply passages connecting the corresponding outer ends of the valve seat and power cylinder and an exhaust passage 25 extending forwardly from the central part of the valve seat, a lug arranged on the inner

side of said shell and engaging said reduced rear part of the core, a piston arranged in said cylinder, a cylindrical slide valve engaging said seat, and a hammer having a lever pivoted on said core and provided with a rear arm which engages said valve and a front arm which engages said piston, and a hammer head arranged on the front arm of the hammer lever.

4. A boiler tube cleaner comprising a body having an outer tubular shell and an inner core, said shell being provided at its rear end with an inlet for a pressure medium and in front of its rear end with an internal forwardly facing shoulder, and said core being provided on its rear part with a rearwardly facing shoulder which engages with said shoulder of the shell, a power piston mounted to slide transversely on said core, means for supplying a pressure medium to and exhausting the same alternately from opposite ends of said piston, a hammer lever mounted on said body and operatively connected with said piston and valve and provided at its front end with a hammer head, a retaining ring having an external screw thread engaging with an internal thread on the front end of the shell and bearing against the front end of said core and provided on its inner edge with a plurality of notches arranged in an annular row, and a locking pin detachably mounted on the front end of said core and engaging with one or another of the notches in said retaining ring.

5. A boiler tube cleaner comprising a body having an outer tubular shell and an inner core, said shell being provided at its rear end with an inlet for a pressure medium and in front of its rear end with an internal forwardly facing shoulder, and said core being provided on its rear part with a rearwardly facing shoulder which engages with said shoulder of the shell, a power piston mounted to slide transversely on said core, means for supplying a pressure medium to and exhausting the same alternately from opposite ends of said piston, a hammer lever mounted on said body and operatively connected with said piston and valve and provided at its front end with a hammer head, a retaining ring having an external screw thread engaging with an internal thread on the front end of the shell and bearing against the front end of said core and provided on its inner edge with a plurality of notches arranged in an annular row, a locking pin having a screw connecting with said core and adapted to engage with one of the notches in said ring, and a key passing through the front end of said locking pin.

JOHN ZILLIOX.
